UNITED STATES PATENT OFFICE.

THOMAS H. HUSTON, OF SHELBYVILLE, ILLINOIS, ASSIGNOR OF ONE-HALF TO
WALTER C. HEADEN, OF SHELBYVILLE, ILLINOIS.

FLUE-STOPPER.

1,119,166.

Specification of Letters Patent.

Patented Dec. 1, 1914.

Application filed December 29, 1913. Serial No. 809,291.

To all whom it may concern:

Be it known that I, THOMAS H. HUSTON, a citizen of the United States, residing at Shelbyville, in the county of Shelby and 5 State of Illinois, have invented certain new and useful Improvements in Flue-Stoppers; and I do declare the following to be a full, clear, and exact description of the invention, such as will enable others skilled in the art 10 to which it appertains to make and use the same.

This invention relates to flue stoppers, and more especially to that class of the latter which employs a thimble in conjunction 15 with a cap piece.

One object of my invention resides in providing a flue stopper, and cap therefor having means coöperating with certain other means carried by the flue stopper for withdrawing the latter from its seat, so that all 20 possibility of soiled hands and other annoyances usually resulting from this operation are eliminated.

Another object of this invention resides 25 in producing a flue stopper and cap which are efficient in operation, simple in construction, and particularly well adapted for the function hereinafter to be ascribed to them.

With these and other objects in view my 30 invention consists of certain novel features of construction and the combination and arrangement of parts as will be more fully described and claimed.

In the accompanying drawings: Figure 1 35 is a fragmentary section of a chimney with my improved flue stopper disposed therein. Fig. 2 is a vertical longitudinal section illustrating the means for removing the thimble. Fig. 3 is a similar view taken at right angles 40 to that of Fig. 2. Fig. 4 is an end elevation of my improved stopper illustrating my improved locking tongues. Fig. 5 is a transverse vertical section taken on the line 5—5 of Fig. 3.

Referring more particularly to the drawings, the thimble 1 comprises a sheet metal 45 body 2 bent into cylindrical form and having its meeting edges brought into engagement and bent into an interlocking joint 3.

In order to permanently close the inner 50 end of the thimble 1, I slash the cylindrical body 2 around its edge so as to form a plurality of tongues 4. The alternate tongues 4 I bend inwardly and at right angles to the cylinder to provide a seat for the head or closing member 5 which is seated thereon.

The remaining tongues 6 are then projected in a similar direction and brought into engagement with the outer surface of said head 5, thereby permanently securing the latter to the cylindrically formed body 2. 60 The advantage of this construction resides in the fact that as the thimble 1 is intended to be inserted in the stove pipe opening of the chimney with the closed end adjacent the chimney flue, the head 5 must be securely 65 fastened by some means absolutely unaffected by heat; consequently by providing the tongues as above set forth in place of solder or other connecting means which would be subject to the disadvantage stated, 70 the head 5 cannot drop from the cylinder and thereby destroy the utility of the invention by permitting the dirt and soot of the chimney to enter the room.

A cap 7, having a diameter slightly 75 greater than that of the thimble 1, closes the outer end of the same, and when said thimble is placed in position within the stove pipe opening, it projects laterally beyond the adjacent end of the latter, covering 80 it completely as well as eliminating the unsightly open end of the thimble, thereby rendering a finished appearance to the room. To retain the cap in position upon the thimble 1 as well as to facilitate the ready withdrawal of the same, I strike the two diametrically disposed inwardly projecting tongues 8 from the outer edge of said cylindrical body 2, and at a central point on the inner surface of the cap 7 I secure a 85 bowed leaf spring 9 which is intended to project within said thimble and have its ends bear against the inner surface thereof and by its resiliency hold the cap in position. In addition to maintaining the cap 7 in position, the tongues 8 also serve another purpose, that is, they provide means for the withdrawal of the thimble from its seat, inasmuch as when cap 7 is partly withdrawn and revolved, the extremities of the spring 90 9 will be brought into frictional engagement with the tongues 8 so that further withdrawal of the cap will also remove the thimble as will be readily understood without further description. Thus it will be 95 seen that by providing the cap 7 in addition to the head 5, the unsightly open end of the thimble is avoided and means provided for the removal of the thimble when it is desired to replace the latter with a stove pipe. 100

105

110

From the foregoing it will be seen that the thimble and cap therefor when inserted in the stove pipe opening thoroughly and practically close the same, and prevent soot or fire from gaining access to the room.

Various changes in the form, proportion, and the minor details of construction may be resorted to without departing from the principle or sacrificing any of the advantages of the invention as claimed.

What is claimed as new is:

1. In a device of the character described, the combination with a thimble having a closure at the inner end thereof and provided with inwardly projecting tongues disposed at opposite points on its inner surface adjacent its outer end; of a cap closing the open end of said thimble, the outer edge of said cap extending laterally beyond the outer end of the latter, and a bowed leaf spring secured intermediate its ends to the central portion of said cap, the extremities of said spring extending to and bearing against the sides of said thimble whereby when said cap is partly withdrawn and re-

volved, said extremities will frictionally engage said tongues for the removal of said thimble.

2. In a device of the character described, the combination with a thimble having inwardly projecting tongues disposed at opposite points on its inner surface contiguous to its outer end, of a cap closing the outer end of said thimble, and a bowed leaf spring secured intermediate its ends to the central portion of said cap, the extremities of said spring extending to and bearing against the sides of the said thimble whereby when said cap is partly withdrawn and revolved, said extremities will frictionally engage said tongues for the removal of said thimble.

In testimony whereof I have hereunto set my hand in presence of two subscribing witnesses.

THOMAS H. HUSTON.
